UNITED STATES PATENT OFFICE.

RICHARD C. McKILIGET, OF NEW ORLEANS, LOUISIANA.

OVERHEAD TROLLEY-WIRE CROSSING.

No. 892,874.

Specification of Letters Patent.

Patented July 7, 1908.

Application filed June 18, 1907. Serial No. 379,611.

To all whom it may concern:

Be it known that I, RICHARD C. McKILIGET, a citizen of the United States, residing at New Orleans, in the parish of Orleans and 5 State of Louisiana, have invented certain new and useful Improvements in Overhead Trolley-Wire Crossings; and I do hereby declare the following to be a full, clear, and exact description of the invention, such as 10 will enable others skilled in the art to which it appertains to make and use the same.

The object of my invention is to produce a simple and cheap overhead trolley wire crossing, which shall be easily adjustable to 15 any angle between the wires desired, and which shall be readily adapted to either a continuous line wire, or to a disconnected line wire.

To these ends, my invention consists in a 20 plurality of metallic arms connected to an insulating center piece. Each of said arms is provided with clamping means for the line wires, and also with tram ways having a raised center portion forming a continuation 25 of the track for the trolley wheel, all as will be more fully hereinafter disclosed.

Referring to the accompanying drawings forming a part of this specification; Figure 1 represents a plan view of my improved trolley crossing. Fig. 2 a sectional view through the center of the same. Fig. 3 a plan view of the same looking from the bottom upward. Fig. 4 is a side elevation of the same. Fig. 5 is an end view of one of the arms showing 30 the wedging piece detached, and the wire in section, and Fig. 6 is a sectional view of one of the arms taken through the line 6—6 of Fig. 2.

Like letters indicate like parts in all views. 40 A indicates a center piece, which may be of insulating or other suitable material. Said piece is provided with a plurality of holes B through which pass bolts or other fastening means C, which bolts hold in place the metallic conducting arms D provided with the inclined slots E and fitted with wedges F adapted to clamp the wires H to the said arms D. The wedges F are provided with a plurality of wings G, on each side of their center line, fitting in corresponding notches in the arms D, as shown, and are hinged between lugs H' carried by said arms by means of a cotter pin I. Said arms D are provided with flanges J on their undersides, which are 50 spaced apart a distance somewhat greater

than the thickness of the trolley wheel, and are also provided with the swell or reinforcement K, which forms a continuation of the track on which the trolley runs after it leaves the wire H. The center piece A fits in cut-away portions in the ends of said arms D, as shown, and is provided with a spacing piece L, also of insulating or other suitable material, and a bolt M passes through the two pieces A and L to secure the whole together. 60 65

The operation of my device is as follows:— If a disconnected line is desired, the wires H are passed through the slots in the arms, as shown, which slots are of a width equal to the thickness of said wires, the wedges F are 70 then forced down upon said wires, so that their wings G enter their corresponding notches in the arms D, and the pins I pass through the ends of the same and the lugs H'. The ends of the wires are next bent up 75 over the pivoted ends of said wedges, as shown, and the same are then securely fastened in place. In case a continuous line is desired, either the same wire H may be continued on over the center piece A and passed 80 through the slot in the opposite arm D, or a separate wire may be passed over said piece A and connect the ends of the wire H, as desired, in which case said separate wire would be joined in any suitable manner, as 85 by twisting, to the respective ends of the wires H.

My trolley crossing being securely fastened in place, before the trolley wheel leaves one of the wires H, it is caught between the lower 90 projecting flanges J of the arms D and is guided in the tram way formed by said arms. Upon leaving the wire H, the trolley wheel immediately takes up, or contacts with, the swell K lying between said arms J and forming a continuous track with the wires H. It is thus continuously guided until it is safely within the flanges J of the first arm D, and is sure to pass on until it strikes the corresponding swell K on the next arm, which in turn 100 guides the said wheel onto the wire H attached to said arm. It will also be seen that my device affords a ready means of providing any angle desired between two crossing wires, for all that is necessary is merely to 105 unfasten one of the bolts C, turn its arm D, around the center piece A, until it makes the desired angle with the other wire, and then secure it in place by passing said bolt C, through the said arm D, and the appropriate 110

hole B, in the piece A. By this simple means I am enabled to change any arm D, or adjust the same to any desired angle with any other arm. By thus moving or adjusting these 5 arms D, so as to make various angles with each other, of course, I also cause the various conductors to make various angles with each other. It will also be seen that I entirely do away with all solder, or other permanent and 10 non-detachable fastenings. My device as a whole is simple to manufacture, there being no parts difficult to make by machinery, or by casting, and is therefore exceedingly cheap as well as efficient.

15 Having thus described my invention, what I claim and desire to secure by Letters Patent, is:—

1. In an electric railway, the combination of a plurality of pairs of independent conductors; an insulated center piece, provided with a series of holes B; and a plurality of arms cut away at their inner ends and detachably connected to said center piece, each of said arms being provided with a slot and 25 means in the same for securing one of said conductors to one of said arms, and each arm also being provided with a pair of integral depending flanges forming a tram way for the trolley wheel, whereby any wire may be 30 readily secured at any desired angle with any other wire and as soon as the trolley wheel leaves any wire it is immediately caught and guided in the said tram way, substantially as described.

35 2. In an electric railway, the combination of a plurality of pairs of independent conductors; an insulated center piece, provided with a series of holes B; and a plurality of pairs of independent arms each arm being 40 detachably connected to said center piece, and each of said arms being provided with a slot and means in the same for securing one of said conductors to one of said arms, each arm also being provided with a pair of de- 45 pending flanges forming a tram way on its under side for the trolley wheel, and an integral swell between said flanges for guiding said wheel, whereby any wire may be readily secured at any desired angle with 50 any other wire and as soon as the trolley wheel leaves any wire it is immediately

caught and guided in the said tram way, substantially as described.

3. In an electric railway, the combination of a plurality of conductors H, provided with turned up ends; an insulated center piece A, provided with a series of holes B; and a plurality of independent arms D, cut away to fit said center piece and provided with holes adapted to register with said holes B, bolts C, securing said arms to said center piece, said arms, also, provided with a slot E, for receiving one of said conductors, and a pivoted wedge F, around which said turned up ends of said conductors fit, for securing 65 said conductors in said slot, and each of said arms being also provided with depending flanges J and a reinforce or swell K, constituting a tram way for the trolley wheel, whereby any wire may be readily secured at 70 any desired angle with any other wire and as soon as the trolley wheel leaves any wire it is immediately caught and guided in the said tram way, substantially as described.

4. In an electric railway the combination 75 of a plurality of conductors H, an insulated center piece A, provided with a series of holes B, and a plurality of arms D, provided with holes adapted to register with said holes B, bolts C securing said arms to said center 80 piece, said arms, also, provided with a slot E for receiving one of said conductors, and a wedge F provided with a plurality of wings G on each side of its center line and fitting corresponding recesses in said arms for 85 securing said conductors in said slot, and each of said arms being also provided with depending flanges J, and a reinforce or swell K constituting a tram way for the trolley 90 wheel, whereby any wire may be readily secured at any desired angle with any other wire and as soon as the trolley wheel leaves any wire it is immediately caught and guided in the said tram way, substantially as described. 95

In testimony whereof, I affix my signature, in presence of two witnesses.

RICHARD C. MCKILIGET.
